UNITED STATES PATENT OFFICE.

SAMUEL LONDON, OF NEW YORK, N. Y.

SHIRT AND GARMENT SUPPORT.

No. 802,765.

Specification of Letters Patent.

Patented Oct. 24, 1905.

Application filed December 30, 1904. Serial No. 238,929.

To all whom it may concern:

Be it known that I, SAMUEL LONDON, a citizen of the United States, and a resident of the city of New York, borough of Manhattan, in 5 the county and State of New York, have invented a new and Improved Shirt and Garment Support, of which the following is a full, clear, and exact description.

This invention relates to shirts or shirt-waists, such as worn by small boys.

The object of the invention is to provide a garment of this kind with means for supporting the trousers in a resilient or elastic manner without recourse to suspenders.

Reference is to be had to the accompanying drawings, forming a part of this specification, in which similar characters of reference indicate corresponding parts in all the figures.

Figure 1 is a front view of a garment with 10 which my invention has been incorporated. Fig. 2 is a side elevation showing a button of my invention which is used in connection with the garment. This view is partially broken away, as will appear. Fig. 3 is a perspective 15 of the button shown in Fig. 2 and illustrating the manner in which the said button is attached to an elastic band. Fig. 4 is a section through the button shown in Fig. 2. Fig. 5 is a horizontal section through a portion of 20 the body of a shirt at the waistband and illustrating the manner of attaching the waistband to the body.

Referring more particularly to the parts and especially to Fig. 1, 1 illustrates an undergarment or shirt, such as worn by a child 25 beneath the blouse or shirt-waist. In its general construction this shirt is of common form. In applying my invention, however, I provide a waistband 2, which passes continuously about 30 the body of the garment at or near the waistline. This waistband is preferably tacked to the material at suitable points 3. In this way the waistband is attached continuously around the garment so as to form free or loose straps 35 4 between the attached points, as will be readily understood. I reinforce the garment and waistband by means of inclined strips 5 of braid or similar material, which strips are securely sewed to the bosom of the shirt, as 40 indicated. These strips 5 are preferably made of a continuous band which extends below the points 3, so as to form loops 6, the said loops being unattached to the material of the garment and depending below the waistband 2, 45 as will be readily understood. These reinforce-

forcing-strips 5 not only prevent the waistband 2 from being torn away, but they also serve to distribute the forces incidental to supporting the trousers or breeches in such a manner as to prevent the garment from pulling tightly in vertical lines passing over the shoulders.

I provide means for supporting the breeches or trousers from the waistband 2. To this end I provide a continuous belt 7, preferably 50 of narrow elastic material, as indicated. At intervals upon this belt the buttons 8 are attached. These buttons preferably consist of two disks 8^a 8^b, formed of leather or similar material. The two disks are normally superposed upon each other, as shown in Fig. 2, and they are each preferably provided with three alining openings 9, through which the elastic belt 7 is passed, as indicated most clearly in Fig. 3. In this figure the disks 8^a 55 8^b are represented as pulled apart, as they could be by sufficient force; but it should be understood that the strands 10 of the belt which are disposed between the two disks normally hold the disks closely superposed 60 one upon the other.

In Fig. 1 I illustrate the manner in which the belt, together with the buttons, may be worn to support the trousers. When the belt is worn as illustrated, the belt would be 65 passed about the body in a horizontal line above the waistband 2, and its ends would be attached together in any well-known manner. The portions of the belt 7 carrying the buttons would then be drawn down into the space 70 between the straps 4 and the body of the shirt, so that the buttons would lie below the waistband. With this arrangement the portion of the belt 7 between the buttons 8 would be disposed in loops 11, which would be supported 75 upon the lower extremities of the reinforcing-strip 5. The breeches would then be attached to the outer disks of the buttons, and the drawers would button to the inner disk. The connection to the shirt would evidently be very resilient, so as to adapt itself 80 readily to active movements of the boy's body. Evidently the buttons may give downwardly 85 individually, and they may shift substantially longitudinally in any direction. Thus they 90 will accommodate themselves to the circumstances. In attaching trousers to the buttons it should be understood that the outermost disk 8^b, as shown in Fig. 3, will be 95 passed through the buttonhole in the trousers. 100 105 110

Having thus described my invention, I claim as new and desire to secure by Letters Patent—

1. A shirt with a waistband having separated points of attachment upon said shirt, in combination with a belt having buttons and supported from said waistband.

2. A shirt having a waistband passing continuously thereabout and attached at intervals thereto, reinforcing-strips disposed in inclined directions and secured to the bosom of said shirt, and a belt supported by said waistband and adapted to support a lower garment.

3. A shirt having a waistband passing con-

tinuously thereabout and attached at intervals thereto, and a belt supported by said waistband and disposed in loops depending between the points of attachment of said waistband, and buttons carried by said loops and adapted to support a lower garment.

In testimony whereof I have signed my name to this specification in the presence of two subscribing witnesses.

SAMUEL LONDON.
